UNITED STATES PATENT OFFICE.

FRANK A. JOSEPH, OF NEW HAVEN, CONNECTICUT, ASSIGNOR TO L. CANDEE & CO., A CORPORATION OF CONNECTICUT.

RUBBER SHOE.

1,336,962.

Specification of Letters Patent. Patented Apr. 13, 1920.

Application filed September 25, 1918. Serial No. 255,565.

To all whom it may concern:

Be it known that I, FRANK A. JOSEPH, a citizen of the United States, residing at New Haven, county of New Haven, and State of Connecticut, have invented new and useful Improvements in Rubber Shoes, of which the following is a full, clear, and exact description.

This invention relates to improvements in rubber shoes, and particularly that class known to the trade as "footholds," the foothold being secured to the leather shoe by means of a strap which passes over the heel box of the latter. The object of the invention is to so construct the foothold as to insure the permanent union of the strap and the members with which it is connected, particularly the sole.

In the manufacture of rubber shoes of the class in question, the strap has customarily been formed with free ends which are led down to the shank of the foothold and vulcanized, independently of one another, to the sole. It has been found in practice that in the said construction the straps frequently pull away from the sole. The cause for this is two-fold: First, each end of the strap necessarily has but a small surface in contact with the sole. Therefore, when the rubber shoe is in position upon the foot the twisting of the latter will not permit the strains upon the strap to be borne equally by the strap ends at all times, and the strap end which has the weaker connection with the sole finally pulls away. Secondly, the shank of the rubber shoe is somewhat stiff and therefore does not hug the shank of the leather shoe sufficiently to bar the entrance of moisture. This moisture attacks the joint between each end of the strap and the sole and weakens the union of the two.

The said defects are completely obviated by the present invention.

The invention will be understood by reference to the accompanying drawings in which,

Figure 1 is a perspective view of a rubber shoe made in accordance with the invention;

Fig. 2 is a plan view of the strap of the rubber shoe in its lay-out form;

Fig. 3 is a development of the heel strap.

By reference to Fig. 1 it will be seen that the shoe comprises an upper A, a sole

B, and a strap C. A lay-out of the strap is shown in Fig. 2. In forming the strap from the lay-out it is folded on the line X so that the wings b, b^x will lie over the wings c, c^x. This folded structure is then turned until the edges 1, 1^x meet and the wing c^x is brought under and secured to the projecting margin 3 of the wing b, the parts assuming the position shown in Fig. 3.

When the strap is built up from the lay-out as just described, the single-ply margins 4 at each side of the base of the strap will be joined to the upper as indicated in Fig. 1. In the said figure the dotted line 6 indicates the rear edge of the upper A, the dotted line 5 indicates the edge of the wing b and the dotted line 7 indicates the marginal edge of a lining L. The triangular portions of the strap bounded by the inner edges of wings b, b^x and the dotted lines 8, Fig. 3, will be joined to the forked shank 75 of the sole B as indicated in Fig. 1. In this manner the shoe will be formed as a multi-ply structure at all points except at the triangular portion D intermediate the inner edges of wings b, b^x. The triangular portion in question, therefore, will constitute a point of relatively greater flexibility. The inner margin of the completed strap structure may be folded over to form the reinforced edge 9, as shown in Figs. 1 80 and 3.

When the foothold thus constructed is drawn upon the leather shoe, the pull upon the strap will cause the flexible shank D to yield so that its surface will uniformly 90 grip the shank of the shoe, the fork of the sole B separating slightly for this purpose. And inasmuch as the flexible shank D connects sections of the base of the strap which ordinarily constitute free ends of the latter, the strains imposed upon one section will be thrown in part upon the other section. Thus the strains are distributed and the tendency of the strap to pull away from the sole is largely overcome.

Having thus described my invention, what I claim and desire to protect by Letters Patent is:

1. A rubber sandal of the character described, comprising an upper, a sole, and a heel strap, said strap having two spaced sections secured to the shank of the sole, the said sections being connected by a relatively

yielding section adapted to be drawn into conformity with the shank of the shoe when the strap is placed in position upon the heel of the latter.

5. 2. A rubber sandal of the character described comprising an upper, a sole, and a heel strap, said strap having a relatively yielding section at its base adapted to hug the shank of a shoe when the strap is in place upon the heel of the latter, the strap being secured to the sole at opposite sides of said yielding section.

15. 3. A rubber sandal of the character described comprising an upper, a sole, and a heel strap, said strap having a relatively yielding section at its base, and the shank of the sole being cut away at the marginal lines of said relatively yielding section.

20. 4. A rubber sandal comprising an upper, a sole and a heel strap, the said strap being formed of a unitary member folded to form a plurality of plies, the ends of the member being joined to each other by lap seams at

the shank of the shoe and also being joined to the rear edges of the upper.

25. 5. A heelless rubber sandal comprising an upper, a sole, and a heel strap secured together, said strap being folded to form a plurality of substantially co-extensive plies one of which is bent around the other to 30 form a reinforcing binding, the folded plies of the strap being joined to the rear edges of the upper by staggered lap seams and being also joined to each other adjacent their junction with the sole.

35. 6. A heelless rubber sandal comprising an upper, a sole, and a one-piece heel strap, said strap being composed of a plurality of folds united to form an endless band of one ply thickness and elastic under the arch, the 40 strap being also united to the rear edges of the upper and sole throughout their extent.

Signed at New Haven, Conn., this 20th day of Sept., 1918.

FRANK A. JOSEPH.
